X-RAY TREATMENT STRUCTURE

Arthur F. Jeans, Toronto, Ontario, Canada

Application April 24, 1937, Serial No. 138,720

7 Claims. (Cl. 250—34)

The invention relates to improvements in X-ray therapy for cancer treatment as described in the present specification and shown in the accompanying drawings that form part of the same.

The invention comprehends the novel construction and arrangement of a group of treatment rooms and an impervious drum common thereto in which windows are so disposed as to emit X-ray beams at such angles that several patients may be treated simultaneously and privately. A distinctive feature of the invention resides in so constructing the rooms relative to the drum that each patient is disposed within 15 the effective distance from the X-ray source.

A further salient feature lies in the provision of revolvable tables, each having a vertical axis about which a patient is adjustable in order to bring the part of the person to be treated in 20 alignment with the axis of rotation and at an angle to the X-ray beam. This enables the patient to be revolved or oscillated in an arc of a circle relative to the fixed beam so as to treat the diseased part from different directions.

By those familiar with the art, it is recognized that the treatment of patients suffering from deep-seated malignant growths, by means of deep X-ray therapy is rapidly entering a new field. X-rays produced by potentials of about 25 200 kv. are now superseded by those produced by potentials from 400 to as high as 1,200 kv. The tubes designed for this purpose are capable of emitting effective radiation from two to five windows, which from the standpoint of economy 30 offsets the increased expenditure involved in such installations and the additional cost of operating the supervoltage therapy apparatus. The nature 35 of these tubes, however, invests them with the disadvantages of immobility. The present invention overcomes this disadvantage by providing for positional movement and adjustment of the patient relative to the tube.

While satisfactory generating equipment is available for such supervoltage machines and 45 while relatively satisfactory X-ray tubes, measuring devices and controls can be installed with little trouble, a suitable and practical method of applying the treatment has hitherto not been developed. The majority of methods suggested 50 by X-ray manufacturers are necessarily limited in their scope by reason of the fact that they are only applicable to conditions in which the patients are capable of movement of their own volition. This does not, however, take care of 55 the large percentage of patients who are unable

to assume or lie in the various positions demanded by existing tables. A supervoltage tube of the type referred to for the purpose of performing the present invention is disclosed in the publication "Radiology" vol. 27, No. 2, pages 208-216, 5 August, 1936. The difficulty in utilizing this tube arises in the treatment rooms, and the main problems encountered are enumerated as follows:

1. Immobilization of the patients, many of whom are required to lie absolutely still for an 10 hour at a time, for which purpose a suitable treatment table must be employed. In practice, the table is about 6.5 feet long, and since any part of the body may require treating and from any angle, the four extreme positions determine 15 the necessary range of movement of the table. The four extreme positions are those which accommodate treatment of the head of the patient. It may be treated from either side, from the top, or from beneath, i. e., under the chin. To embrace such plural positions, a circular range of about ten feet is essential.

2. The maintaining of the proper skin target distance (S. T. D.) is an all-important factor controlling the dose when the tube is working at 25 full output. The skin target distance is the actual distance from the source of radiation (the anode or anticathode) to the surface of the patient. As this distance is decreased the intensity 30 of the radiation increases and vice versa. According to modern equipment, a skin target distance of not more than 1 metre is necessary. The intensity of the X-ray beam is similar to that of light radiation in that it decreases with increasing distance from the source according to 35 the square root law. Intensity is controlled at the tube by two main factors, the voltage and current through the tube; both of which are limited by various technical problems. Hence the intensity of the tube is limited, and not the least 40 of these problems is the cooling of the anode. The intensity is measured in roentgens and modern practice demands an intensity of 10 to 20 roentgens per minute.

Inasmuch as the skin target distance must be 45 maintained, the problem of arranging four patients around the tube so that the tables or beds may lie one metre distance from the tube anode or target and at the same time allow free play of about 10 feet for the 6.5 foot tables, is one 50 that must be overcome before the maximum advantages of the tube may be had. A simple partitioning of the treatment rooms will not bring about this result, as a study of the problem will show. So far as I am aware, the design- 55

ers of four portal tubes have not been able to offer a satisfactory solution to the problem that is overcome by the present invention.

A further consideration, that of scatter radiation, makes it necessary to partition the space around the tube into separate compartments for each patient and to so construct the partitioning walls as to embody an X-ray absorbent substance in order that radiation thrown back from the body of one patient will not radiate deleteriously to another patient concurrently undergoing treatment.

This invention presents a structure and method of treatment by which the immobility of super voltage machines is not only overcome, but augmented by flexibility and accuracy exceeding that of existing shock proof apparatus.

A most vital feature of the present invention resides in the arrangement of the treatment rooms combined with the angle at which the X-ray beam is introduced into each of them, as illustrated in the drawings. Four rooms are shown, and according to the arrangement by which one patient can lie partially below another in a different room, complete freedom of movement is obtainable and strict privacy is assured.

Referring to the accompanying drawings, Figure 1 is a vertical sectional view of the group of rooms and showing patients undergoing treatment.

Figures 2 through 5 are respective perspective views of rooms 1 to 4 inclusive.

Figure 6 is a slightly modified form of the invention in which the rooms are grouped with respect to a vertical drum.

Figure 7 is a vertical sectional view through the drum showing the X-ray tube.

Referring particularly to Figures 1 to 5 inclusive, the reference numeral 10 denotes a horizontally arranged drum impervious to X-rays from the interiorly mounted X-ray tube 11. This drum is immovably mounted and forms a part of the building.

45 The horizontal wall 12 forms the floor of room 1 and merges into a side of the drum below the centre thereof. The drum has a window 13 radially disposed to direct an X-ray beam 14 into this room at a slight upward angle.

50 The treatment chamber is provided with a platform or bench 15 supporting the table 16. The platform extends outwardly from the drum at right angles to its length, and the table is of the tilting type provided with a conventional universal movement whereby it may be shifted longitudinally and transversely. Additionally, in order to carry out the present invention, a special rotatable mounting 17 is incorporated in the table by which it is revolvable about the vertical 55 axis 18. The patient is adjusted so that the skin target is in alignment, or substantially so, with said vertical axis. The irradiation thus intercepts the vertical axis at an angle. A power or manual operating means may be employed to 60 turn the table on its rotatable mounting. The motion may be circular or oscillatory about the axis of rotation.

65 The horizontal wall 19 extends from the drum 10 on the opposite side thereof to that of the wall 12 and at a higher elevation, as shown. The wall 19 constitutes the floor of the room 2 for separately treating another patient, illustrated as recumbent upon the table 20 supported on the platform or bench 21. This table is similar in 70 construction to that aforementioned, and its ver-

tical axis of rotation is denoted at 22 and is intersected by the beam of irradiation rays 24 emanating from the window 25. This window is positioned normal to the window 13 so as to direct its beam at an angle to a vertical line projected upwardly from the drum.

5 A partitioning wall 26 forms a continuation of the floor wall 19 and extends from the top of the drum at an upward angle over the wall 12 to a point at which it is joined to the vertical partitioning wall 27. By this construction it will be evident that sufficient space is available to provide for the required movement of the tables and the patients in both rooms with respect to focus point within the drum.

10 The horizontal wall 28 forms the floor of the room 3 and is situated beneath the wall 19 but on a slightly higher elevation than the floor 29 of room 4. The wall 28 terminates short of the drum and has a vertical partitioning wall 30 15 joined to the horizontal wall 31 subjacent to the drum and joined thereto by the wall 32.

15 The room 3 is equipped with a platform or bench 33 supporting the table 34 rotatable about the vertical fixed axis 35 intersected by the beam 36 downwardly and outwardly directed from the window 37 diametrically opposite the window 13.

20 Accordingly, the table 34, together with the patient, may be freely manipulated in juxtaposition to the beam source while maintaining the 30 required distance for the skin target.

25 The walls 30 and 31 form an alcove in room 4 below the drum for the purpose of enabling the table 38 to be accommodated below and partially beneath the table 34 and to have sufficient 35 space in which to freely operate within the required distance from the centre of X-ray source. The table 38 is supported upon the platform or bench 39 extending outwardly from the alcove. The vertical rotative axis 40 of the table is bisected by the beam 41 from the angularly disposed window 42 diametrically opposite the window 25.

30 It will be seen that by this construction the vertical axes of the four tables are in a common 45 plane at right angles to the drum axis, and that each patient can be centred to the proper skin target distance.

35 By referring particularly to Figure 1, the simplicity with which four extreme cases from the 50 point of view of difficulty of handling is shown. In room 1, a patient suffering from a mediastinal tumor, cancer of the lung, or cancer of the aesophagus, is seated in a position of maximum comfort, while receiving a treatment posteriorly. 55 The back of the seat, which may be made with strong Celluloid, combined with a simple automatic centering device, provides for accurate centering of the beam which is diaphragmed down to the required area. Anteriorly, the patient can be treated with the same ease in room 3. Room 2 is shown as containing a medullablastoma patient receiving post operative treatment to the spine. A case of cancer at the base 60 of the tongue is shown in room 3, whereas in room 4 a patient is shown undergoing treatment for cancer of the orbit, antrum or nasopharynx.

65 Inasmuch as skin target distance is a factor of major importance in X-ray therapy, the present invention provides means by which the proper 70 distance can be obtained and maintained by the radiologist and changes made to suit his individual technique with a high degree of flexibility.

75 Adverting to the modification shown in Figure 6, this is substantially the same as the treatment 75

room structure already described with the exception that the impervious drum 43 is vertically arranged and the windows 44 are slightly differently disposed to have similar angles of incidents with the vertical axes of rotation of the tables (not shown) supported on the benches 45. In this construction the walls 60 compose a treatment room for a patient. A part of the vertical drum 43, containing the X-ray tube, protrudes 5 into the room and has a portal or window for downwardly directing an X-ray beam at a suitable angle for treatment. On the far side of this room is a similar room (not shown) into which a part of the drum protrudes and has a 10 similarly disposed window or portal for a beam. At the left a still further treatment room is provided by the walls 61; which room has an elevated floor and is let into the rooms aforesaid so that the drum will break into the inner walls thereof 15 and thus allow another window to discharge a beam into this room. At the right hand side of the drum an opposing elevated room is formed by the partitioning walls 62 for the treatment of a fourth patient. By elevation of the floors 20 of the left and right rooms, alcoves may be formed in the other two rooms whereby sufficient space is provided to enable tables to be manipulated so as to maintain the skin target distance 25 in carrying out the treatment.

30 In Figure 7 is a typical mounting of an X-ray tube in a drum. The impermeable drum is denoted at 44 and has windows as at 45. The drum extends between opposite walls 46 that form a part of the treatment rooms. Beyond these 35 walls, the insulators 47 of the X-ray tube 48 are arranged as shown. The filament shield is shown at 49 and the lead target is denoted at 50. The X-ray tube herein illustrated is of the type now manufactured in the United States of America 40 for potentials in excess of 400 kilovolts and is operated under constant evacuation by suitable pumps. The cathode filament ejects electrons which fall through a potential difference of about 1200 kilovolts and then strike the target. Most 45 of the energy is converted into heat at the target, but about one-half of one per cent of the former is converted into X-ray radiation. The body of the tube in the room—or in the rooms according to the present invention—where treatments are given, consists of a steel drum encased in heavy 50 lead which prevents undesired X-rays from striking the patients. The openings, denoted at 45, in the lead provide the windows or portals and may have diaphragms to restrict the radiation to 55 a field of proper size and shape for the part of the body to be irradiated. Speedy vacuum pumps and tight joints are used to secure the requisite reduction of absolute pressure within the tube. Lead gaskets under heavy pressure are employed 60 to prevent leakage. Potential gradients are reduced by the use of shields at intermediate points. The shields and electrodes are supported and housed by glazed porcelain bushings 47. The 65 vacuum pump connection is behind a shield which prevents gaseous discharges from getting into the evacuation pump.

What I claim is:

1. The combination in an X-ray treatment structure, of an impervious drum, a plurality of treatment rooms grouped about the drum and having dividing walls meeting the annual extent of the drum whereby a portion of the annual surface of the drum is exposed in each room, the floors of the rooms being disposed at different elevations and in overlying relation such that they

5 relatively interfit about the drum within unobstructed target distance, an X-ray tube extending through the drum, and windows so arranged in the drum as to angularly project a beam into each room, and a treatment table supported in each room for rotation about a vertical axis coincident with the skin target distance for treatment of a patient.

2. The combination in an X-ray treatment structure, of an impervious drum horizontally disposed, a plurality of treatment rooms grouped about the drum and having dividing walls meeting the annual extent of the drum whereby a portion of the annual surface of the drum is exposed in each room, the rooms being disposed at 10 different elevations and in overlying relation such as to produce alcoves in certain of the rooms whereby space is provided therein for the treatment of patients within skin target distance of the drum, an X-ray tube housed in the drum, 15 windows so arranged in the exposed annual surface of the drum as to project a beam into each room, at a downward or upward angle, and a treatment table supported in each room for rotation about a vertical axis at a skin target distance 20 from the source of radiation.

3. The combination in an X-ray treatment structure, of an impervious horizontal drum so incorporated in dividing walls of a group of horizontal treatment rooms as to compose a part 30 of the wall structure thereof, the rooms being disposed at different elevations and in overlying relation such as to produce alcoves in certain of the rooms whereby space is provided therein for the treatment of patients within a skin target 35 distance of the source of radiation within the drum, treatment tables operably supported in the rooms, means providing a mounting for each table and including an element whereby the table is rotatable about a fixed vertical axis located at 40 the skin target distance, an X-ray tube in the drum, and windows so angularly arranged in the drum as to project a beam into each room at an angle to the vertical axis of rotation of each 45 table.

4. In an X-ray treatment structure, a horizontal impervious drum for containing an X-ray tube, a horizontal wall leading from the periphery of the drum substantially at the top thereof and forming a floor of a treatment room thereabove, 50 an upwardly inclined wall meeting the periphery of the drum at the top thereof and terminating in a vertical partitioning wall, a window in the top of the drum for angularly projecting a beam into the room above mentioned, a subjacent wall 55 horizontally extending from the drum beneath the aforesaid inclined wall and spaced therefrom so as to compose a part of an adjoining treatment room, a lateral window in the drum for projecting a beam into the room at an upward 60 angle between said subjacent wall and said inclined wall, a horizontal wall disposed below the drum and offset thereto beneath the first mentioned horizontal wall, vertical and horizontal partitioning walls joining the offset wall and the 65 bottom of the drum and forming a part of an intermediate room, a lateral window in the drum for projecting a beam into this room at a downward angle, a horizontal wall beneath the aforesaid subjacent wall and forming the floor of a 70 room therebelow, and a window in the bottom portion of the drum for projecting a beam downwardly into the last mentioned room.

5. In an X-ray treatment structure, the combination of a group of treatment rooms having 75

- divisional walls and having relatively elevated floor walls, an impervious drum built into the rooms as a unit with said wall structure, the arrangement of the drum being such as to have
- 5 a peripheral portion exposed in each room, a window disposed in each of the exposed peripheral portions of the drum, an X-ray tube mounted interiorly of the drum for discharge of beams through the windows, a table in each room, and
  - 10 a support therefor whereby the table may be adjusted and turned about a vertical axis at a skin target distance from the radiation source, the entire aforesaid structure being characterized in that the wall structure of the rooms is so constructed and arranged with respect of the drum that space is provided thereabout whereby the several tables are capable of adjustment and rotation about the respective vertical axes of their supports within skin target distance of the radiation source of the X-ray tube.
  - 15 6. The combination in an X-ray treatment structure, of an impervious drum, a plurality of treatment rooms grouped about the drum and having the drum incorporated as part of the wall structure thereof such as to expose a part of the annular surface in each room, the rooms being constructed in superimposed and overlying relation such as to produce alcoves in certain of the
  - 20
  - 25

rooms adjoining the drum whereby space is provided for the treatment of patients within skin target distance of the drum, an X-ray tube housed in the drum, windows so arranged in the exposed annular surface of the drum as to angularly project a beam into each room, and a treatment table supported in each room for turning movement about a fixed vertical axis at a skin target distance from the source of radiation.

7. The combination in an X-ray treatment structure of an impervious drum, four treatment rooms grouped about the drum and having dividing walls meeting the annular extent of the drum whereby a portion of the annular surface of the drum is exposed in each room, the rooms being disposed at different elevations and in overlying relation such as to produce alcoves in certain of the rooms whereby space is provided therein for the treatment of patients within skin target distance of the drum, an X-ray tube housed in the drum, windows so arranged in the exposed annular surface of the drum as to project a beam into each room, at a downward or upward angle, and a treatment table supported in each room for rotation about a vertical axis at a skin target distance from the source of radiation.

ARTHUR F. JEANS.
